UNITED STATES PATENT OFFICE

GEORGE M. FORGES, OF ORANGE, NEW JERSEY, ASSIGNOR TO KAUMAGRAPH COMPANY, OF NEW YORK, N. Y., A CORPORATION OF NEW YORK

CARTON AND RETAINING DEVICE

Application filed October 4, 1929. Serial No. 397,350.

My invention relates to a new and improved combined carton and retaining device.

One of the objects of my invention is to provide a new and improved carton and retaining device which shall be especially useful in packing small articles of wearing apparel, such as hosiery, or the like.

Another object of my invention is to provide a carton having a simple, cheap and efficient retainer which can be readily applied in order to firmly retain small articles of wearing apparel or the like.

Another object of my invention is to provide a carton having a retaining device which can be readily applied and which is automatically but releasably locked in position when it has been inserted in the proper position.

Other objects of my invention will be set forth in the following description and drawings which illustrate a preferred embodiment thereof, it being understood that the above general statement of the objects of my invention is intended merely to generally explain the same and not to limit it in any manner.

Fig. 1 is a perspective view, part of the carton being broken away to show the improved device.

Fig. 2 is a sectional view on the line 2—2 of Fig. 1.

Fig. 3 is a detail view of the holding member.

Fig. 4 is a detail perspective view showing how the holding member is assembled with the retaining member.

The carton C is of any suitable type, and it is preferably made of ordinary cardboard. This carton is adapted to contain hosiery, neckties, handkerchiefs, or other small articles of wearing apparel. The carton C may be provided with a covering sheet C' of any suitable type and it may also be provided with a cover (not shown) of any suitable type. It has been proposed to retain the articles within a carton by means of tapes or the like as this is desirable when the carton is shipped, in order to firmly hold the articles in position. However, the de-

vices heretofore proposed have not been adjustably connected to the carton, and they were relatively expensive. According to my invention, the carton is provided with one or more holding devices 1, which are preferably U-shaped, and they may be formed of cardboard or similar light bendable material. As shown in Fig. 4, the vertical legs of each retaining member 1 are provided with slots 2. The legs of the retaining members 1 are connected to holding members 3. These are preferably made of suitable metal and have tongues 4 stamped out therefrom. As shown in Fig. 2, the tongues 4 are bent so as to firmly grip the legs 60 of the retaining members 1. I prefer to have the points of the tongues 4 enter the said legs to avoid injuring the articles held within the carton C. The upper ends of the holding members 3 are pointed and said 70 points are preferably bent outwardly.

I have assumed, for convenience, that the carton is held in the horizontal position, although this is of course immaterial for the purposes of my invention.

In order to apply the retainers, they are simply pushed into position until they abut and preferably somewhat compress the hosiery, neckties, or the like. The outwardly bent ends 3 make it possible to readily 80 insert the retainers 1 because the holding members 3 are preferably made of spring metal, so that each said member 3 can readily slip into the carton, when it is moved inwardly. However, the upward or outward movement of said holding members 3 is restrained because their outwardly bent points then dig into and grip the side walls of the carton C. When the articles in the carton C are compressed by the retainers 1, 90 the reaction tends to force said retainers outwardly. The points of the holding members then engage the inside surfaces of the side walls of the carton, and said points can then bend more in the lateral direction 95 to dig into said side walls. That is, the points of the holding members are only bent laterally to a slight extent when said holding members are forced inwardly, and said points are bent outwardly in the lateral 100

direction by the outward movement of said holding members. However, I include in my invention the use of holding members sufficiently stiff to retain their initial shape.

5 Each of the retaining members 1 is preferably made with sufficient springiness so that its legs press firmly against the side walls of the carton. Likewise, it would not be departing from my invention if the

10 side walls of the carton C were provided with closely spaced grooves or recesses into which the points of the holding members 3 could enter. This would make it unnecessary for said points to dig into the side

15 walls of the carton.

Although the holding members 3 releasably lock the retainers 1 in position, it is simple to manually remove said retainers 1 or to destroy them so as to readily remove

20 the contents of the carton C.

I have shown a preferred embodiment of my invention, but it is clear that numerous changes and omissions could be made without departing from the spirit of my invention.

I claim:

A device for retaining merchandise in a container comprising a relatively stiff retaining member having legs depending from extremities thereof for insertion between the side walls of the container and contents thereof, said legs being provided with holding means, said holding means having reversely outwardly directed points.

35 In testimony whereof I affix my signature.

GEORGE M. PORGES.
